US00D759163S

(12) **United States Design Patent**
Manowski et al.

(10) **Patent No.:** **US D759,163 S**
(45) **Date of Patent:** ** *Jun. 14, 2016

(54) **LABEL FOR AN INHALER**

(71) Applicant: **CELON PHARMA Spółka Akcyjna**, Kielpin (PL)

(72) Inventors: **Bogdan Szczepan Manowski**, Kielpin (PL); **Maciej Wieczorek**, Kielpin (PL)

(73) Assignee: **Celon Pharma S.A.**, Kielpin (PL)

(*) Notice: This patent is subject to a terminal disclaimer.

(**) Term: **14 Years**

(21) Appl. No.: **29/480,631**

(22) Filed: **Jan. 28, 2014**

(30) **Foreign Application Priority Data**

Jul. 30, 2013 (EM) 002283309-0002

(51) **LOC (10) Cl.** **19-08**
